UNITED STATES PATENT OFFICE.

CHARLES H. TAYLOR, OF CALHOUN FALLS, SOUTH CAROLINA.

RAILROAD-CROSSING SIGNAL.

Application filed May 17, 1927. Serial No. 192,012.

This invention relates to vehicle energy actuated signal devices for railroad crossings and has for its object to provide a construction which will be more economical in cost and 5 more efficient in operation than those heretofore proposed.

With these and other objects in view the invention consists in the novel details of construction and arrangements of parts more 10 specifically hereinafter disclosed and particularly pointed out in the claims.

Referring to the accompanying drawings forming a part of this specification in which like numerals designate like parts in all the 15 views:—

Fig. 1 is a perspective view, partially broken away, illustrating the application of this invention to a railroad crossing;

Fig. 2 is a side elevational view of the invention as disclosed in Fig. 1;

Fig. 3 is a transverse sectional view of the parts shown in Fig. 2 taken as on the line 3—3 thereof and looking in the direction of the arrows;

Fig. 4 is a detail sectional view of an electric circuit closer taken as on the line 4—4 of Fig. 2 and looking in the direction of the arrows;

Fig. 5 is a side elevational view of a semaphore at the road crossing and a resetting device associated therewith; and

Fig. 6 is a transverse sectional view of the railroad track illustrating the application of the resetting device thereto, said figure further being an end elevation of the parts shown in Fig. 5.

This device may be applied to either single or double track railroads, although in the drawings only one track has been shown for simplicity. This track comprises the usual rails 1 and 2 supported in the usual manner by the cross-ties 3 and the limitations of the intersecting roadway are represented by the lines 4 and 5. In the customary space between two adjacent cross-ties at a point relatively remote from the crossing and in close proximity to one of the rails such as 1, is disposed a support 8 preferably of cement for an operating lever 9 pivoted as at 10 to said support, said lever comprising a relatively short power arm 11 and a relatively long work arm 12, one on either side of the pivot 10. The support 8 is placed to some considerable depth in the ground so that it will be substantially immovable and the pivot 10 is so arranged that the upper surface of the power arm 11 of

the lever 9 will lie in substantially a horizontal plane under and in contact with the bottom surface of the rail 1 of the track, the entire lever extending laterally away from 60 said track.

The end of the long arm 12 of said lever is pivotally connected as at 13 to the bottom end of a substantially vertical link 14 the upper end of which is pivotally connected as at 15 65 to the extremity of the short arm 16 of a second power transmitting lever 17 pivoted as at 18 to a supporting post 19 substantially immovable with respect to the ground. The other arm 20 of the lever 17 is much longer 70 than the arm 16 so that the distance traversed through the instrumentality of the lever 17 will be multiplied as was the distance similarly multiplied through the instrumentality of the first mentioned or operating 75 lever 9.

To the free end of the arm 20 of the lever 17 is secured one end of a connector 25 which may be a solid rod, a steel cable, or any other suitable member, the other end of which is 80 secured to one branch of a bell-crank 26 pivotally supported as at 27 to a post 28 placed along side the railroad.

The other branch of the bell-crank 26 has secured thereto one end of a connector 30 85 which, like the connector 25 may be a rod, a cable, or other suitable member, the other end of which is attached as at 31 to the end of an operating crank or lever 32 adapted to oscillate the semaphore signal arm 33 about 90 the pivot 34 on the post 35 at the crossing. The connector 30 may be suitably strung along the railroad in any convenient manner either on pulleys, rollers, or otherwise, either close to the ground, or elevated to suit operating conditions.

From the foregoing and with particular reference to Figs. 2 and 3 it will be observed that as the wheels of the vehicle passing over the track assume positions opposite the operating lever 9, the weight of said vehicle will be transferred to the rail 1 causing a movement thereof in a direction toward the ground. Stated in other words, it is practically impossible to construct a railroad track so that there will not be yielding in a vertical direction. No matter how well the ties 3 may be embedded in the ballast of the road bed, there will be a depression of the rails when an object of considerable 105 weight rolls thereover. This vertical depression of a rail will vary in proportion to

the load carried, but depressions of from one-eighth to one-quarter of an inch are not unusual.

Therefore when a vehicle passes over the 5 rail 1, the same will be caused to move downwardly and, inasmuch as the upper surface of the power arm 11 of the operating lever 9 is in contact with the bottom surface of the rail, said lever will be oscillated about its 10 pivot 10. The ratio of the lever arms 11 and 12 may be made as desired but in actual practice an efficient ratio has been found to be 1 to 8. In other words, the length of the short or power arm 11 is made approximately one-eighth the length of the other or work arm 12, so that the movement of the rail 1 through a distance of one-eighth of an inch would cause the link 14, pivotally connected to the extremity of the work arm 12, to move vertically a distance of one inch. The link 14 is also pivotally connected to the extremity of a power arm 16 of the power transmitting lever 17, the arm 16 being substantially one-eighth the length of the work arm 20 of said 25 lever, so that the movement of said link through a distance of one inch would cause the extremity of the work arm 20 to move through a distance of eight inches, all as will be readily understood. This movement in 30 turn causes an oscillation of the bell-crank 26 and the operation of the semaphore signal 33 through the instrumentality of the connectors 25 and 30. In other words, when the 35 train passes the lever 9 the semaphore arm 33 will be moved from its depending position shown in Fig. 2 to an elevated position represented by the dotted lines in said figure, where the same will be readily visible to one approaching and attempting to cross the 40 railroad track at the crossing.

It is within the scope of this invention to also provide at the crossing an audible signal in addition to the visible signal arm 33. The 45 audible signal generally indicated by the numeral 40, may be of any character such as a bell, adapted to be connected in circuit with any suitable source of electric power not illustrated but readily understood. The electric circuit will be normally open so that the 50 signal will not be actuated until a train, approaching the crossing, will operate the levers 9 and 17 as above described. Near the end of the arm 20 of the lever 17 there may be provided a member 41 electrically connected, 55 as through said lever and pivot therefor, to the wire 42 leading to one side of the source of current, not illustrated. From the other side of said source there will be provided a wire 43 for conducting the current to and through 60 the operating mechanism of the audible signal 40, said current leaving said mechanism as over the wire 44 electrically connected to a member 45 adapted to be contacted by the member 41 carried by the lever 17. In other 65 words, when the lever 17 is actuated, the

member 41 will be carried downwardly, see Figs. 2 and 4, and in this movement it will contact with its companion member 45 carried by the post 28, closing the circuit through the audible signal 40. This contact 70 will be maintained between the members 41 and 45 so long as there is sufficient weight in the rail 1 opposite the lever 9 to actuate the lever 17. To insure a more positive engagement of the switch members 41 and 45, there is provided a guard or guide bar 46 secured to the post 28 to confine the movement of the end of the arm 20 of the lever 17 as will be readily understood from the drawings.

The operating lever 9 is preferably located 80 at a remote point with reference to the crossing so that a train moving at a considerable speed may actuate the signal device long before the train reaches the crossing, to give an ample warning, as will be readily understood. 85 From the above description it will be obvious that the device will be continually operated so long as a heavy vehicle is passing over the rail opposite the operating lever 9. If the train is of sufficient length the signal will be continued at the crossing for a considerable period of time, but in some instances only a locomotive or very short train will be passing over the track. In this instance, the signal will be given at the crossing for a very short 90 period of time so that it would be possible for the locomotive to approach the crossing without giving due warning. Therefore it is very desirable if not absolutely necessary to provide for the repeated or continuous functioning of the signal device at the crossing.

This may be accomplished in several ways, one of which is illustrated in Figs. 1, 2 and 3. That is to say, the operating unit comprising the lever 9 as previously described is located 105 along the track at a remote point from the crossing, the exact position of said location being determinable by the nature of traffic on the railroad. In addition to this remote operating unit, there may be provided one or 110 more intermediate operating units. That is to say, and with particular reference to Fig. 1, there may be provided an intermediate operating lever 50 associated with the rail 1 exactly as was the operating lever 9 and a 115 duplicate thereof. Said lever 50 will be connected as by the link 51 to a power transmitting lever 52 which is a duplicate of the lever 17, said lever 52 having secured to the end thereof one end of a connector 53 the other 120 end of which is secured to a lug 54 extending outwardly from one of the branches of a bell-crank 55 similar to the bell-crank 26 above described and pivotally supported on an intermediate post 58. Instead of having the one connector 30 between the bell-crank at the remote operating unit and the member 32 secured to the semaphore arm 33, said connector 30 may be replaced as by the connector 56 joining the bell-crank 26 to the crank 55, 125 130

and a second connector 57 joining said bell-crank 55 and the semaphore 33 all as will be clear from Fig. 1. Thus the weight of the vehicle on the track will operate the semaphore arm 33 through the instrumentality of the lever 9 at the remote unit, and the weight of said vehicle will also operate said semaphore 33 when it passes each of the intermediate operating levers such as 50, thus prolonging the warning.

In the foregoing description the semaphore arm 33 has been given an intermittent oscillatory movement. In Figs. 5 and 6 is disclosed a modification of this invention wherein the semaphore arm will be raised into visual position and left in said position during the approach of a vehicle on the track, said semaphore being reset, or lowered from said visual position when said vehicle reaches a point opposite the semaphore. This is accomplished by mounting on the pivot 60 a semaphore arm 51 similar to the semaphore arm 33 but having rigidly secured thereto a toothed sector 62 adapted to be engaged by a pawl 63 pivoted as at 64 to a bracket 65 secured to the post 66.

The pawl 63 has rigidly formed therewith a laterally extending lug 70 provided with a pin 71 adapted to work in the slot 72 disposed in the upper end of a substantially vertical link 73 the lower end of which is pivotally connected as at 74 to the end of a lever 75 pivoted as at 76 to a rigid support 77 therefor, said lever 75 extending beyond said pivot to form the short power arm 78 disposed beneath the rail 1 of the track. In other words, the lever 75 is a substantial duplicate of the operating lever 9. When the vehicle on the track passes the remote unit, the connector 30 will raise the semaphore arm 61 from its full line position to the dotted line position shown at 79 in Fig. 5. During this movement the toothed sector 62 will be partially rotated causing the pawl 63 to slip over the teeth of said sector. However, the semaphore arm 61 is prevented from accidentally falling from its visual position by said pawl by virtue of the fact that the pivot 64 of said pawl is so disposed, and the shape of the pawl is such, that the weight of the laterally extending lug 70 will cause the pawl 63 to remain in engagement with the toothed sector. This may be stated in other words, namely, the mass of material constituting the lug 70 lies to one side of the pivot 64, and is of greater weight than the mass of material constituting the toe of the pawl 63 which lies substantially beneath said pivot 64. The result of course is that the weight of the lug 70 overbalances the weight of the toe of the pawl 63 and thus tends to keep said toe in engagement with the teeth of the sector 62. With the semaphore arm 61 held in raised position, as at 79, the train or other vehicle may continue in its path toward the crossing without requiring inter-

mediate operating units. When the vehicle reaches the point opposite the lever 75, the rail 1 will be depressed by the weight of said vehicle causing said lever to oscillate and move the link 73 upwardly, during which movement the lower extremity of the slot 72 in the end of said link will contact with the pin 71 carried by the lug 70 of the pawl 63, and in the continued upward movement of said link the pawl 73 will be oscillated about 75 its pivot 64 with resultant disengagement of the toe of said pawl from the teeth of the sector 62. When this occurs the semaphore arm 61 will, through its weight, drop to the full line position shown in Fig. 5, remaining there until the next following vehicle operates the mechanism to again raise the same.

All of the foregoing description has been directed to movement of a vehicle on the track in the direction of the arrow in Fig. 1. Should the vehicle be moving in the opposite direction it would be desirable to also give a signal at the crossing and this may be readily accomplished by providing similar operating units along the track. That is to say, at a remote point on the other side of said crossing there may be provided the operating unit 100 exacting similar to the operating unit shown and described in the other figures of the drawings, and at one or more intermediate locations there may be provided an auxiliary operating unit 101 similar to the intermediate operating unit described above. Both the units 100 and 101 will be suitably connected to bring into vision at the crossing 100 the semaphore arm 102 exactly similar to the semaphore arm 33.

The operating units 100 and 101, as well as the semaphore arm 102 may be disposed on the same side of the track as the operating units previously described, or they may be on the opposite side of the railroad track as conditions demand. It might be necessary to change or otherwise modify the exact details of each operating unit in order to give a signal during the movement of a vehicle on the track, but such change would be within the scope of this invention and in all probability would consist only in a mere reversal of the details of construction of the operating units 100 and 101.

From the foregoing disclosure it will therefore be seen that by this invention there is provided a warning device for a railroad crossing comprising a signal of either visual or audible character which is located at the crossing. In combination with this signal there is provided a track including a section of rail for a railroad vehicle said rail secured as usual to the cross-ties and being 125 undeformed in any manner for the purpose of this invention. Lastly there is provided means extending between two adjacent cross-ties to actuate the signal by the weight of the vehicle on the section of the rail, said means 130

coacting with said section through a co-relationship requiring no modification of said rail and cross-ties so that it will be apparent that this device can be installed on an existing railroad without disturbing the construction thereof. In other words the posts 8 and 77 are of dimensions permitting their placement in the usual space between two adjacent cross-ties so that said ties need not be moved or replaced, whereby the rail always has the usual amount of support and therefore will not be subjected to variable or undue strains. These means constitute connections between the signal and the section of the rail, said connection being of a distance multiplying nature and more specifically including compound levers one of which extends beneath and contactingly engages the bottom of said section of rail. This invention thus avoids the heretofore known actuating means which have required a separate section of rail, or a member secured to the rail and adapted to be depressed by an overhanging portion of the wheel of a vehicle or required some other change or modification in the usual road construction. It also obviates the necessity of providing any auxiliary equipment on the vehicle or roadway or both such as up-standing or depending members adapted to strike and oscillate a companion member in order to actuate the signal device. In fact this invention is of such character that no change whatever has to be made in the rail or the track equipment, or the vehicular equipment so that this device is well adapted for any railroad.

It is obvious that those skilled in the art may vary the details of construction as well as arrangements of parts without departing from the spirit of the invention; therefore it is not desired to be limited to the foregoing disclosure except as may be required by the claims.

What is claimed is:

- 45 1. In a vehicle energy actuated warning device for a railroad crossing the combination of a signal; an undeformed section of track rail supported at usual intervals; and connections between said signal and said section to actuate said signal by the weight of a vehicle disposed on said section, said connections mounted independently of said section and its support.
- 50 2. In a vehicle energy actuated warning device for a railroad crossing the combination of a signal located at said crossing; an undeformed section of track rail supported at usual intervals and located at a point remote from said crossing; and connections between said signal and said section to actuate said signal by the weight of a vehicle disposed on

said section, said connections disposed to multiply the deflection of said section and mounted independently of said section and its support.

65 3. In a vehicle energy actuated warning device for a railroad crossing the combination of a signal; an undeformed section of track rail supported at usual intervals; and connections between said signal and said section to extend beneath the latter to actuate said signal by the weight of a vehicle disposed on said section, said connections disposed to multiply the deflection of said section and mounted independently of said section and its support.

70 4. In a vehicle energy actuated warning device for a railroad crossing the combination of a signal; an undeformed section of track rail supported at usual intervals; and connections between said signal and said section to actuate said signal by the weight of a vehicle disposed on said section, said connections including a lever extending beneath said section and said connections mounted independently of said section and its support.

75 5. In a vehicle energy actuated warning device for a railroad crossing the combination of a signal; an undeformed section of track rail supported at usual intervals; and connections between said signal and said section to actuate said signal by the weight of a vehicle disposed on said section, said connections including compound levers one of which extends beneath and contactingly engages the bottom of said section and said connections mounted independently of said section and its support.

80 6. In a vehicle energy actuated warning device for a railroad crossing the combination of a signal located at said crossing; a track including a supported section of rail for a railroad vehicle; and means coacting with said section to actuate said signal by the weight of said vehicle on said section, said means mounted independently of said section and its support.

85 7. In a vehicle energy actuated warning device for a railroad crossing the combination of a signal located at said crossing; a track including a section of rail for a railroad vehicle, said rail secured as usual to cross-ties; and means extending between two adjacent cross-ties to actuate said signal by the weight of said vehicle on said section, said means mounted independently of said section and cross-ties and coacting with said section through a corelationship requiring no modification of said rail and cross-ties.

90 In testimony whereof I affix my signature.

CHAS. H. TAYLOR
